CLAIM

I claim the ornamental design for a lens cleaning device, as shown and described.

DESCRIPTION

FIG. 1 is a left front perspective view thereof,
 FIG. 2 is a top plan view thereof,
 FIG. 3 is a front elevation view thereof,
 FIG. 4 is a back elevation view thereof
 FIG. 5 is a bottom plan view thereof; and,
 FIG. 6 is a left view thereof.
 The right side is a mirror image to the left side.
